UNITED STATES PATENT OFFICE.

SETURÔ NAGAO, OF TOKYO, JAPAN.

UNLOADING MACHINE.

Application filed December 16, 1925, Serial No. 75,705, and in Japan December 17, 1924.

Unloading machines, the principal object of the invention being to provide a machine of this character having a traveling grab in combination with a chute automatically movable into the path of movement of the grab for receiving material discharged from the grab and out of said path for permitting free passage of the grab, whereby the speed of operation, and consequently the 10 capacity of the machine, is greatly increased.

With the foregoing and other objects in view, which will appear as the description proceeds, the invention consists in the novel features of construction and combination of 15 parts which will be more fully described hereinafter and particularly pointed out in the claims.

In the drawings accompanying and forming part of this specification,

20 Fig. 1 is a side elevation of a traveling crane equipped with the improved unloading apparatus in position for unloading a barge, the dotted lines indicating the operative position of the chute;

25 Fig. 2 is a front elevation of the view shown in Fig. 1;

Fig. 3 is a plan view thereof;

Fig. 4 is a front view, on an enlarged scale, of the improved unloading device 30 proper;

Fig. 5 is a side view thereof, showing the device broken away from the crane;

Fig. 6 is a fragmentary front view showing the means for connecting the grab and 35 counterweight for movement together;

Fig. 7 is a fragmentary side view illustrating the operation of said connecting means; and

Fig. 8 is a plan view thereof.

40 The same characters of reference designate the same parts in the different figures of the drawings.

Referring to the drawings, and especially to Figs. 1 and 2, the apparatus is shown carried by a crane 36, which is mounted on rollers so as to permit movement thereof in a direction parallel with the dock or other place of use, and which crane carries an inclined belt or conveyor 32 for the disposal of 50 material delivered by the grab, it being understood that any other suitable form of conveyor may be used, since the conveyor is not a part of the present invention.

The unloading machine proper comprises 55 a pair of vertical guide rails 7 attached to the crane 36, between which rails is disposed

a frame 13 provided at its opposite ends with projections or shoes 16 and 17 in engagement with the rails 7 and adapted to travel vertically thereon. Suspended from the frame 13 is a grab 1, comprising a pair of jaws 14 pivotally connected together by links 15 attached at their upper ends to a pulley 18 around which passes a main cable 11, said cable passing over one of a pair of pulleys 20 mounted on the crane frame 36 and secured on a windlass 21. A second or auxiliary cable 12 passes over the other one of the pair of pulleys 20 and is secured at one end to the grab frame 13.

In the crane frame 36, immediately back of the guide rails 7, is pivotally mounted, as at 2^a, a chute 2 which is adapted to discharge into a hopper 3. The chute is so mounted that it will normally occupy an inclined position, with its upper end well in the path of movement of the grab, as indicated in dotted lines in Figs. 1 and 5, so that when the grab is in its elevated position any material discharged therefrom will fall on to the chute and be thereby delivered to the hopper 3.

In order to retain the chute 2 in vertical position while the grab is being hoisted, and to insure the tilting of the chute at the proper time, I provide a counterweight 24 vertically slidable between the rails 7 above the grab, said counterweight being connected with the chute by a pair of cables 23 passing over pulleys 22 at the top of the crane frame and around pulleys 22^a near the bottom of said frame, as shown clearly in Fig. 5. The weight of the counterweight is such that when free to exert itself on the cables 23 the chute will be retained in vertical position. However, when the grab is being hoisted with a load of material, as it nears the top of the guide bars 7 the frame 13 engages the underside of the counterweight 24 and lifts it so that upon continued upward movement of the grab the counterweight is carried with it, thus slackening the cables 23 and permitting the chute 2 to swing into inclined position below the grab as shown in dotted lines in Fig. 5, whereupon the cable 12 may be operated to open the grab thereby to discharge its contents on to the chute in a manner which will be readily understood.

From the foregoing it will be obvious that the relative motion of the grab and chute is of the utmost importance, especially after

the grab has discharged its contents and is being lowered. It will be understood that the grab descends quickly by gravity, and if it should happen that the chute has not entirely swung out of the way the grab would strike the chute and thereby have its descent arrested. Consequently, I have illustrated in Figs. 6, 7 and 8 a mechanical device for preventing such an accident. In this device two pairs of spring clamps 26 are secured to the counterweight 24 and provided with clamping portions extending therebelow and adapted to straddle the shoes 16 of the frame 13 when the latter is raised into contact with the counterweight, as shown clearly in Figs. 6 and 7. The shoes 16 are preferably formed with double wedge shaped cam surfaces, as shown in Fig. 7, for engagement with the spring clamps, so that when the grab is being raised said surfaces will first spread apart the clamps, which, after passing over the highest points of the wedges will spring inward and engage the lower inclined surfaces thereof, so that when the grab starts downward it carries the counterweight with it until further descent of the counterweight is stopped by the cables 23 after the chute has arrived at its vertical position, whereupon the spring clamps will again be spread by the cam surfaces of the grab shoes and thus release the grab from the counterweight and permit continued descent of the grab.

Having thus described my invention, what I claim is:

1. In an apparatus of the character described, the combination of a vertically movable grab, a pivoted chute adapted to swing

into an inclined position intersecting the path of movement of the grab, a counterweight disposed above the grab and adapted to be moved thereby during its upward movement, means connecting said counterweight with said chute whereby the latter is normally retained in vertical position out of the path of the grab and is automatically released when the counterweight is raised, and cooperating means carried by said grab and counterweight for resiliently connecting them together whereby the grab will carry the counterweight with it during a portion of the downward movement of the grab.

2. In an apparatus of the character described, the combination of a vertically movable grab, a pivoted chute adapted to swing into an inclined position intersecting the path of movement of the grab, a counterweight disposed above the grab and adapted to be moved thereby during its upward movement, means connecting said counterweight with said chute whereby the latter is normally retained in vertical position out of the path of the grab and is automatically released when the counterweight is raised, spring clamps carried by said counterweight and extending below the same, and cam members carried by said grab and adapted to be engaged by said spring members thereby to cause movement of the counterweight with the grab during a portion of its downward movement.

In testimony whereof I affix my signature.

SETURÔ NAGAO.
